UNITED STATES PATENT OFFICE.

STEVE MAKAY, OF CLEVELAND, OHIO.

DESIGN FOR A STRINGED MUSICAL INSTRUMENT.

Application filed January 16, 1922. Serial No. 210. Term of patent 14 years.

To all whom it may concern:

Be it known that I, STEVE MAKAY, a citizen of the United States, residing at Cleveland, in the county of Cuyahoga and State of Ohio, have invented a new, original, and ornamental Design for Stringed Musical Instruments, of which the following is a specification, reference being had to the accompanying drawings, forming a part hereof.

The figure is a perspective view showing my new design.

I claim:—

The ornamental design for a stringed musical instrument as shown.

STEVE MAKAY.
